RECODER BAR

William G. H. Finch, Newtown, Conn.

Application September 16, 1944, Serial No. 554,427

2 Claims. (Cl. 234—70)

1

My present invention relates to facsimile scanning systems and more particularly to scanning means for use in connection with chemically treated paper at a facsimile receiver.

Essentially, my invention contemplates the use of a helical type of scanning device in place of the stylus. That is, the chemically treated paper on which a record is to be made is unwound from a roll of material and by appropriate feeding devices moved along with respect to a drum and blade. The paper moves over a blade which is spring biased toward the drum. The drum has a one-turn helical wire secured thereto.

The use of the single helical wire types of scanner in connection with a spring biased blade as contemplated by the present invention eliminates excessive wear and trouble in prior stylus type facsimile receivers. The single wire has no single point of excess wear and is completely supported by the drum on which it is wound. The wire thus need not necessarily be limited to a diameter as small as $1/100$ of an inch, since its contact with the paper and pressure on the paper against the knife blade is only tangential. Consequently, the wire may be even larger in diameter. The edge of the knife blade, however, against which the paper is pressed should be of the order of $1/100$ of an inch or less in width. This blade, however, is a stationary member spring biased into contact with the helical wire and not subject to excessive wear.

Accordingly, another object of my invention is the provision of a facsimile scanning device for a facsimile receiver intended to act on chemically treated paper wherein the scanning device and elements in contact with the paper will not be subject to excessive wear.

Still another object of my invention is the provision of the helical wire type scanning device for facsimile scanning systems especially adapted for facsimile receivers.

These and many other objects of my invention will become apparent in the following figures and drawings in which:

Figure 1 is a schematic view illustrating the principle of operation of my invention.

Figure 2 is a top plan view of a device embodying my invention.

Figure 3 is a view in elevation of one side of the device of Figure 2.

Figure 4 is a view in elevation of the other side of the device of Figure 2.

Figure 5 is a view of the knife blade taken from line 5—5 of Figure 4 looking in the direction of the arrows.

Figure 6 is a view of the knife blade taken from line 6—6 of Figure 4 looking in the direction of the arrows.

Figure 7 is a cross sectional view of the knife blade and scanning drum taken at line 7—7 of Figure 2.

Referring now to Figure 1, I have here shown in highly schematic form the principles embodied in my invention. The chemically treated paper 10 passes over the knife blade 11 and beneath the scanning drum 12. Scanning drum 12 has secured thereto in any suitable manner, as, for instance, by welding, soldering or brazing, the wire 13 which is wound helically in one turn of the order of 360° around the drum 12. The paper 10 and drum 12 are stationary just before the start of any scanning operation. Also, at the start, or just before the start of any scanning operation, portion 13' of the wire 13 is in position where it is about to press the paper 10 against the knife blade 11.

When the scanning operation begins, the drum 12 rotates in the direction indicated by arrow 14, and the paper is moved $1/100$ of an inch in the direction indicated by the arrow 15—that is, the full movement of the paper 10 during a complete revolution of the drum 12 is $1/100$ of an inch. During this revolution of the drum 12 and the movement of the paper 10, continuously successive portions of the wire 13 are brought into contact with the paper 10 and press the same against the blade 11. The point of contact passes along the wire 13 from portion 13' to portion 13''. Consequently, the point of contact 13a, during a single revolution of the drum 12, moves entirely across the paper 10 in the direction indicated by the arrow 20.

The drum 12 and the feed mechanism herein-after described for the chemically treated paper 10 are interrelated so that each revolution of the drum 12 produces a movement of the paper 10, in the direction indicated by the arrow 15 for a distance of the order of $1/100$ of an inch. That is, where the scanning lines are 100 lines per inch, then the paper will be moved $1/100$ of an inch during the scanning operation. Where the scanning operation is at 60 lines per inch, then the paper will be moved forward $1/60$ of an inch during the scanning operation. The drum 12 will make a complete revolution during each scanning operation to produce a single line. At the end of each scanning operation, the drum 12 will be brought to a stop and on receipt of a synchronizing impulse will start once more. Immediately after the portion 13'' of the wire 13 has left

the paper at the completion of the scanning operation, the portion 13' of the wire 13 is in position to begin the scanning operation. Consequently, no return movement or lost motion of any kind is required for scanning. Nor are a multiplicity of scanning styli required for this purpose.

It will be obvious, therefore, that an extremely high speed of scanning may be maintained. Where synchronism is not an important factor, the scanning operation may be absolutely continuous—that is, the drum 12 may rotate continuously and, by reason of the integrated drive between the drum 12 and the feed for the paper 10, the scanning lines on the paper 10 will follow each other at appropriately spaced intervals of $1/100$ of an inch or $1/60$ of an inch depending on the degree of intelligibility required.

Where the driving motors for the transmitter and receiver are highly accurate so that a variation in speed of no more than 5% between the two systems will exist, synchronization is not essential. Where, however, extremely accurate results are required, then the drum 12 may be synchronized in a manner shown in connection with Patent No. 2,295,572. While this patent does not show synchronization of a helical scanner device, the synchronizing system described therein is applied to control the movement of the drum carrying the paper and may as readily and without any variation at all be applied to the scanning drum 12 of the present invention. Accordingly, such synchronizing systems require no specific description here, and the specific synchronizing system constitutes no specific part of the present invention, except, of course, that synchronizing systems may be used.

In Figures 2, 3 and 4, I have shown a specific embodiment of the invention of Figure 1 wherein all of the elements are mounted on the base 25. 40 Shaft 21 of motor 26 is by means of the coupling 28 connected to the shaft 29 which rotates in bearing 30. Shaft 29 drives gear 32 which, in turn, drives the larger gear 33. Gear 33 is mounted on shaft 34 which is rotatably mounted on the swinging bracket arm 35 hereinafter described. Gear 36 also mounted on shaft 34 drives the larger gear 37 mounted on shaft 38, which in turn is rotatably mounted on the swinging bracket 35. Small gear 39 also mounted on shaft 38 drives the larger gear 40 mounted on the shaft 41. Shaft 41 is journaled in the bearing 42 of swinging bracket 35 and carries at its inner end one disc 44 of the clutch 45. The other disc 46 of clutch 45 is driven by disc 44 by means of the friction plate 47; the said disc 46 of clutch 45 is connected to and drives the scanning drum 12. Shaft 50 of the scanning drum 12 is appropriately journaled at one side within the clutch 45 and at the other side in the swinging bracket 35.

Swinging bracket 35' is pivotally mounted about the stud 51 on the bearing 30'. The swinging bracket 35 is pivotally mounted about the shaft 29. The brackets 35 and 35' have extensions 55 and 55' respectively by which they may be manually grasped and lifted up. When the ends 55 and 55' are lifted, the brackets rotate about their respective pivots 29 and 51 to lift up the scanning drum 12 and the associated gear train therefor. This permits simplified threading of the paper through the mechanism in a manner hereinafter described.

Guide rollers 60 and 61 for the paper are mounted respectively on shafts 62 and 63 which are journaled in opposite swinging brackets 35 and 75

35'. When the swinging brackets 35 and 35' are lifted up together with the scanning drum 12 and the guide rollers 60 and 61, then, as shown in Figures 3 and 4, the paper 10 may be threaded over roller 60 under the scanning drum 12 and over roller 61 and then to the paper draw rolls 70 and 71 which are operated in a manner hereinafter described.

10 The ends 55 and 55' of the swinging brackets are slotted at 72 and 72' respectively in order to receive the locking device 75. The locking device on each side comprises a standard 76 on which the end 55 or 55' rests. The standard 76 is provided with a vertical slot 77 within which is pivotally mounted at 78 the locking bar 79. The locking bar 79 is threaded at its upper end and a nut 80 is mounted thereon. When the end 55 of the swinging bracket 35 is placed on top of the standard 76, the locking bar 79 is swung upwardly so that it enters the slot 72 of the end 55 of member 35, and the nut 80 is then tightened down on top of the extension 55 of the swinging bracket 35 to hold the same securely in place.

25 When it is desired to raise the scanning drum 12 and the swinging bracket 35 in order to rethread the paper or for other purposes, then the nut 80 need only be loosened and the locking bar 79 be swung aside so that these members may be raised.

30 The paper draw rolls 70 and 71 are driven from the shaft 59 of the scanning drum 12. The worm gear 85 (Figures 2 and 3) mounted on the extension 86 of shaft 50 through bracket 35' drives the spiral gear 87 mounted on shaft 88. Shaft 88 is journaled in appropriate bearings in the standards 90 and 91 mounted on the base 25. Worm gear 93 on shaft 88 drives the spiral gear 94 on the upper draw roll 70. Appropriate tensioning means may be provided with respect to the draw rolls 70 and 71 to drive them together so that the drive of the draw roll 70 will cause rotation of the draw roll 71. Draw rolls 70 and 71 have an appropriate friction surface in order to readily draw the paper 10 between them.

35 The paper 10 is provided in the form of the supply roll 100 mounted on an appropriate shaft 101 and is drawn therefrom under the guide roll 102, then over the guide roll 60, under the scanning drum 12, over the guide roll 61, and then through the draw rolls 70 and 71 which draw the paper out. Appropriate tensioning means may, if desired, be provided on the shaft 101 of the supply roll 100 to ensure an even feed of paper.

40 The blade 11 is mounted on the transverse standard 110 supported on the base 25 of the apparatus. As seen in Figures 6 and 7, the transverse standard 110 is a solid member supported by appropriate brackets 111, 111' on the base. Member 110 has a groove 120 in the upper surface thereof, the said groove communicating with a number of vertical holes 121. The blade 11 is an inverted "T" shaped member having the blade portion 11 as above described and a flange base 122 which rests in the groove 120 on the base thereof. Compression springs 125 in each of the vertical holes 121 bear upwardly against the flange 122 of the blade 11 tending to drive the blade up.

45 The blade 11 is prevented from accidental removal by the top plate 130 having the slot 131 (Figures 5 and 7) through which the plate 11 projects, slot 131 being sufficiently narrow so that the flange 122 cannot be pushed therethrough. When the swinging brackets 35 and 35' are raised, the compression springs 125 can

drive the blade 11 up so that the flange 122 bears against the underside of the top blade 139. When, however, the swinging brackets 35 and 35' are lowered, the wire 13 on the scanning drum 12 presses the plate 11 down against the action of compression springs 125 as shown in Figure 7. When the chemically treated paper 10 has been threaded through in the manner previously described and the swinging bracket arms 35 and 35' have been lowered, the scanning wire 13 on scanning drum 12 presses the paper against the blade 11.

Now as previously described in connection with Figure 1, for each revolution of the scanning drum 12, the portion of the wire 13 in contact with the paper 10 and blade 11 traverses the scanning drum longitudinally and thus traverses the paper. The plurality of springs 125 ensure that there will always be appropriate pressure between the wire 13 and the blade 11 at the point of contact so that this moving point on wire 13 acts as a fulcrum on which the rigid blade 11 pivots. A synchronizing system exactly like that disclosed in the specification of United States Letters Patent No. 2,295,572, may be applied to the scanning drum 12 and may act on the plate 46 of clutch 45. Where such a start-stop synchronizing system is used, extreme accuracy in the facsimile reproduction will be obtained.

The amount of the wire in contact with the paper and the blade is determined by the softness of the paper itself; that is, the extent to which the paper will be compressed by the wire pressing against the blade. For this purpose, therefore, the springs 125 pressing the blade upwardly should exert just sufficient pressure to obtain good contact of the blade against the paper and the paper against the wire without compressing the paper. However, since such chemically treated papers may be very thin and the coatings thereon very fine, the paper has substantially no compressibility and the marking thereon will be exceedingly sharp, determined, since the blade is a non-flexible rigid member as shown in Figure 7, only by the tangential portion of the wire in contact with the paper and the area of the paper in contact with the blade.

The wear on the recording element is not confined to a single small area of $1/100$ of a square inch, but to longitudinal elements of relatively tremendous area which are successively brought into contact with the paper.

Thus a further difficulty which frequently occurred in connection with stylus recording is obviated. Previously, the sharp point of the stylus tended sometimes to scratch the recording paper and often collected dust and particles which (owing to the content of the paper itself) often consisted of carbon particles which tended to smudge the recording.

By the utilization of my present apparatus, a sharp point which would tend to collect such

particles is obviated. Also, by my invention, a wire of a diameter greater than .01 inch may be used to make a line .01 inch wide or even less.

In the foregoing, I have described my invention only in connection with a specific preferred embodiment thereof. Many variations and modifications of my invention should now be obvious to those skilled in the art. Accordingly, I prefer to be bound not by the specific disclosures herein but only by the appended claims.

I claim:

1. In a facsimile receiver of the type having a rotatable drum and a helical member projecting from the surface thereof; a blade mounted adjacent said drum, the edge of said blade extending along a line parallel to the axis of said drum, spring members engaging the rear edge of said blade and causing its front edge to bear against said drum, said blade having a depth such that it forms a non-flexible rigid construction in its longitudinal direction, said spring members causing said rigid blade to bear tangentially against and pivot on a point on said helical member, rotation of said drum causing the pivot point on said helical wire to move along said blade, said blade supporting means comprising a longitudinal support for said blade, a groove in the surface of said support for receiving and guiding the base of said blade, recesses in said support communicating with said groove, said spring members being positioned in said recesses and bearing against the rear edge of said blade, and means for limiting the movement of said blade out of said groove under the influence of said spring members.
2. In a facsimile receiver of the type having a rotatable drum and a helical member projecting from the surface thereof; a blade mounted adjacent said drum, the edge of said blade extending along a line parallel to the axis of said drum, spring members engaging the rear edge of said blade and causing its front edge to bear against said drum, said blade having a depth such that it forms a non-flexible rigid construction in its longitudinal direction, said spring members causing said rigid blade to bear tangentially against and pivot on a point on said helical member, rotation of said drum causing the pivot point on said helical wire to move along said blade, said blade supporting means comprising a longitudinal support for said blade, a groove in the surface of said support for receiving and guiding the base of said blade, recesses in said support communicating with said groove, said spring members being positioned in said recesses and bearing against the rear edge of said blade, means for limiting the movement of said blade out of said groove under the influence of said spring members, said means comprising a flange extending from the base of the blade, and means at the open end of said groove engaging said flange.

WILLIAM G. H. FINCH.
